UNITED STATES PATENT OFFICE.

AUGUST C. DUMKE AND AUGUST F. DUMKE, OF MANITOWOC, WISCONSIN.

AUTOMATIC SAFETY STOP-MOTION.

SPECIFICATION forming part of Letters Patent No. 331,689, dated December 1, 1885.

Application filed July 31, 1885. Serial No. 173,187. (No model.)

To all whom it may concern:

Be it known that we, AUGUST C. DUMKE and AUGUST F. DUMKE, citizens of the United States of America, residing at Manitowoc, in the county of Manitowoc and State of Wisconsin, have invented certain new and useful Improvements in Automatic Safety Stop-Motions, of which the following is a specification, reference being had therein to the accompanying drawings.

This invention has for its object to at once and automatically arrest the action of the engine in the event of the breaking of the driving-belt or its slipping off its pulley or wheel; and the invention consists of the combinations of parts, including their construction, substantially as hereinafter described and claimed.

In the accompanying drawings, Figure 1 is a side elevation of our improved automatic stop or cut-off for engines. Fig. 2 is a similar elevation taken at right angles to the plane of Fig. 1, with the parts shown as tripped. Fig. 3 is also a view in elevation of the same, but taken from the same side of Fig. 1, also with the parts shown as tripped; and Fig. 4 is an enlarged detail view.

In the embodiment of our invention we employ a vertically-sliding sleeve, A, in connection with the usual valve-tripping mechanism, comprising the valve-tripping rods K, the "walking-beam" or centrally-pivoted lever e, the shaft e', having an arm, m, and the rod n, connected to the governor. The sliding sleeve A is supported upon the standard B, mounted upon the frame-like casting or base a, and has a boxing, A', cast upon one side to support the shaft e'. In the opposite side of said sleeve is a vertical slot, i, through which is passed a headed screw or stop, h, to limit the vertical movement of the sleeve, and to prevent lateral movement or displacement.

From the lower end of the sliding sleeve A, preferably on the side carrying the shaft e', depends an arm, C, which is offset from the sleeve, and pointed or made conical at its lower end, the function of which will appear further on.

G is the driving-pulley or band-wheel, with its shaft-box b, cast with two arms, b', branching therefrom in a substantially vertical plane, being slightly curved away from the shaft-

box, and pivoted in the bottom and top portions of the frame-like casting or base a of the standard B. The upper arm, b', of the band-wheel or pulley shaft-box b is provided with an inwardly curved or extended arm, d, upon the free end of which is supported the lower end of the arm or extension C of the sleeve A when the latter is in its elevated normal position. The driving-pulley or band-wheel has its shaft, as usual, geared, as shown at f, to the governor-shaft. The driving-belt is passed over the driving-pulley or band-wheel in the direction shown in Fig. 1, and when in operation the driving-pulley assumes the position shown in Fig. 4, and in the event of the breaking or slipping off of said driving-belt from its pulley the latter, together with its connected parts, will automatically move laterally into the position indicated by dotted lines in said Fig. 4. When the driving-belt is applied as above stated, the inward movement of the arm d is regulated by reason of its contact near its inner end with a downwardly-extended projection of the frame-like casting or base a, or it may be with the casing of the governor-shaft, and when thus held its outer end is in a plane directly under the end of the conical shaft C.

In operation it will be observed that when the vertically-sliding sleeve A is raised, and the driving-belt applied to the driving-pulley or band-wheel, the inwardly curved or extended arm d of the upper arm, b', of the pulley shaft-box will be in such a position as to receive the end of the arm or extension C on its upper surface, and in the event of the belt breaking or its slipping off the pulley or wheel G the weight of the sliding sleeve A, bearing upon the shaft-box of said pulley or wheel out of the plane of its center of gravity, will have the effect to move said shaft-box with the pulley or wheel laterally, which movement of said shaft-box will permit the slipping of the extension C off the arm d, and the consequent downward movement or descent of the sliding sleeve, which will cause the rocking of the lever e, which will act through the rods K to close the steam-valves, thus shutting off the steam from the piston-cylinder, and stopping the action of the engine.

From the foregoing it will be seen that the

usual governor mechanism for tripping the steam-valves in effecting the proper feeding of the steam to the piston-cylinder is utilized to also aid in tripping the steam-valves to 5 stop the action of the engine, as stated, in the event of accident to the driving-belt. Besides, it will be seen that the action of the parts is automatic and instantaneous, insuring perfect immunity from further or serious accident, as might otherwise occur.

Having thus fully described our invention, what we claim, and desire to secure by Letters Patent, is—

1. In a valve-cut-off mechanism, the sliding sleeve carrying the shaft operating the valve-tripping rods, and having an extension or arm resting upon a lateral arm of the pivoted support of the driving-wheel or pulley-shaft, substantially as and for the purpose set forth.
2. In a valve cut-off mechanism, the slotted sliding sleeve engaged by a stop and carrying the shaft operating the valve-tripping rods, said sleeve having a pendent arm or extension with a tapered or conical lower end and resting upon a lateral arm of the pivoted shaft-box extensions of the driving wheel or pulley, substantially as and for the purpose specified.

3. In a governor-valve cut-off, the driving-pulley or band-wheel having its shaft-box provided with two arms, one of said arms having an inwardly curved or extended arm for supporting a pendent arm or extension, and pivoted by said arms to permit of the automatic lateral movement of the pulley in the event of the slipping or breaking of the driving-belt, substantially as shown and described.

4. In a governor-valve cut-off, the combination, with the sliding sleeve having a depending arm, and the valve-operating rods, the said sliding sleeve carrying the shaft of the said valve-operating rods, of the driving-pulley having its shaft-box provided with two arms, one of said arms having an inwardly curved or extended arm, and said arms being pivoted to permit of the automatic lateral movement of said pulley, substantially as shown and described.

In testimony whereof we affix our signatures in presence of two witnesses.

AUGUST C. DUMKE.

AUGUST F. DUMKE.
